(57) **CLAIM**

The ornamental design for a game kit, as shown and described.

DESCRIPTION

1. Game kit

1.1 is a top, right, front perspective view of a game kit comprising a case and game pieces, showing my new design;

1.2 is a top, left back perspective view thereof;

1.3 is a top, right, front perspective view of the case component, shown separately for clear disclosure;

1.4 is a top, right, front perspective view of 1.1, showing the game kit in an exploded state;

1.5 is a top perspective view showing the game pieces in an exploded state and separately for clear disclosure;

1.6 is a bottom perspective view thereof;

1.7 is a top plan view thereof;

1.8 is a bottom plan view thereof; and

1.9 is a bottom plan view of the case component.

The hatched lines shown in the claimed design depict contrast in appearance. The broken lines in reproduction 1.9 depict portions of the game kit that form no part of the claimed design.
